METHOD AND APPARATUS FOR DRYING

Ross H. Buckwalter, Joliet, Ill., assignor to Star
Peerless Wall Paper Mills, Chicago, Ill., a cor-
poration of Illinois

Application November 17, 1934, Serial No. 753,457

7 Claims. (Cl. 34—48)

My invention relates to a method and apparatus for drying and is concerned primarily with the removal of moisture from a continuously moving web of material.

5 The principal object of my invention is to devise a method of drying and an apparatus for effectuating the same in which a continuously moving web, arranged in a succession of overlapping folds, is subjected to the action of a drying 10 medium, usually heated air, the web being turned over at periodic intervals to expose both sides thereof to the medium.

A further object is to devise an apparatus of the 15 type indicated in which the drying medium is so directed relative to the moving web that the latter is characterized by a floating or billowing action that enhances and expedites the drying operation.

These and further objects of my invention 20 will be set forth in the following specification, reference being had to the accompanying drawing and the novel means by which said objects are effectuated will be definitely pointed out in the claims.

In the drawing:

25 Figure 1 is a diagrammatic, sectional elevation of my improved apparatus, as taken on the line 1—1 in Fig. 2, looking in the direction of the arrows.

Fig. 2 is a section taken along the line 2—2 30 in Fig. 1, looking in the direction of the arrows.

Fig. 3 is a sectional, perspective view of a modified duct construction for feeding the drying medium to the moving web.

The apparatus disclosed in this application is 35 more particularly intended for use in connection with a process of making washable wall paper as disclosed in my co-pending application, Serial No. 753,456 filed on even date here-with, because of its capacity for handling a large 40 quantity of paper within a comparatively re-stricted space, thus avoiding the otherwise neces-sity of lengthening the production line by the addition of the festoon type of drying rack which is ordinarily employed to dry wall paper. In 45 many installations, such a change would neces-sitate the demolishing and rebuilding of a portion of the factory, but this step is avoided by the use of my apparatus. For purpose of illustration, the apparatus will be described in connection with 50 the drying of a web of paper, but it will be under-stood that the invention is not so limited, and is suscep-tible of other and broader uses in the field of drying.

Referring to Figs. 1 and 2 of the drawing, the 55 numeral 10 represents standards which may be

arranged in oppositely disposed pairs along the length of the apparatus and to which are secured a number of vertically spaced rail or side bars 11, 12, 13, 14 and 15, the side rails 11 occupying the lowermost positions and the remaining bars being 5 spaced upwardly therefrom in the numerical order indicated. The foregoing arrangement of stand-ards and side rails represents diagrammatically a suggested type of construction for my improved apparatus, and it will be understood that these 10 elements are more specifically referred to for the purpose of indicating a means of supporting other and more important parts of the apparatus as hereinafter described.

At the right end of the apparatus, as viewed 15 in Fig. 1, a shaft 16 is journaled in and extends between the side rails 11 and has affixed to one extremity thereof a gear 17 which may be appro-priately driven by any suitable source of power (not shown). A roll 18 is mounted on the shaft 20 16 between the side rails 11 and a similar roll 19 is also appropriately journaled in the same rails at the opposite end of the machine. Over this pair of rolls operates an endless belt 20 whose upper or web-supporting portion is moved con-tinuously at some predetermined and constant 25 speed toward the right, as viewed in Fig. 1.

A sprocket 21 is also mounted on the shaft 16 and through a chain 22 drives a sprocket 23 fixed to the extremity of a shaft 24 which is journaled 30 in and extends between the side rails 13. A roll 25 is mounted on the shaft 24 between these rails and a similar roll 26 is mounted for rotation be-tween the same side rails at the opposite end of the apparatus. Over the rolls 25 and 26 moves 35 an endless belt 27 at the same speed as the end-less belt 20 and the upper or web-supporting por-tion of the former belt moves in the same direc-tion as the corresponding portion of the latter belt. 40

A sprocket 28 is also mounted on the shaft 24 and through a chain 29 drives a sprocket 30 pro-vided on a shaft 31 that extends between and is journaled in the side rails 15. A roll 32 is fixed to the shaft 31 between the rails 15 and over this 45 roll and a pair of spaced, guide rolls 34, which are located at the opposite end of the apparatus, operates an endless belt 33. The opposite ex-tremity of this belt operates over a roll 35 which is located somewhat to the left of the apparatus, 50 as viewed in Fig. 1, and at an elevation below that of the roll 32, so that between the roll 35 and the upper guide roll 34, the web-supporting por-tion of the belt 33 is inclined to the horizontal, 55 while between the upper guide roll 34 and the roll 35

32, the web-supporting portion of the belt 33 is substantially horizontal and parallel to, and moving in the same direction and at the same rate of speed, as the corresponding portions of the belts 5 20 and 21.

A gear 36 meshes with the gear 17 and is mounted on a shaft 37 that is bridged between and is journaled in the side rails 12 and, between these rails, a roll 38 is fixed to the shaft 37. A 10 similar roll 40 is rotatably mounted between the rails 12 at the opposite end of the apparatus and over the rolls 38 and 40 operates an endless belt 39 whose upper or web-supporting portion moves at the same rate of speed as the corresponding 15 portion of the belt 20, but in the opposite direction.

A sprocket 41 is fixed to the extremity of the shaft 37 and through a chain 42 drives a sprocket 43 that is mounted on the extremity of a shaft 44 which is journaled in and is bridged between the 20 side rails 14. A roll 45 is fixed to the shaft 44 between the rails 14 and an endless belt 46 operates over the roll and a similar roll 47 that is rotatably mounted on and between the rails 14 at the opposite end of the apparatus. The upper or 25 web-supporting portion of the belt 46 operates in the same direction as, and at the same rate of speed, as the corresponding portion of the belt 39.

From the foregoing, it will be understood that 30 the drying apparatus comprises a plurality of endless belts which are spaced from each other in a vertical direction and whose directions of movement are so controlled that a web of material that is deposited, for example, on the belt 33, will 35 follow a substantially sinuous path in moving through the apparatus. This arrangement makes for compactness and a capacity for handling a relatively large quantity of material within a rather restricted space.

In order to supply a drying medium to the apparatus, which medium is usually heated air, co-operative pairs of ducts 48 extend lengthwise of the apparatus on opposite sides of, and at substantially the same elevation as, the web supporting portions of the several belts. Each of these ducts is provided with a plurality of apertures 49 and the ducts are connected by means of a manifold 50 to a suitable source of heated air. The emission of the air from the several apertures 49 may be controlled by suitable dampers 51 that are located in convenient locations along each duct. In Fig. 1, there has been illustrated two manifolds 50 for feeding air to the several ducts, but the arrangement and number 55 of such manifolds may be varied as desired.

As an important feature of my apparatus, I prefer to employ a so-called crimping mechanism comprising a pair of cooperating rolls 52 and 53 which draw therebetween a continuous web of 60 material 54 and deposit the same upon an endless belt 55 that is supported at one end upon the usual roll 56. The rolls 52 and 53 are driven at some constant speed and such that the peripheral speed of these rolls is somewhat greater than 65 the linear speed of the endless belt 55. The web 54 will therefore be delivered to the belt 55 in a somewhat crimped arrangement, that is, in a succession of overlapping and irregularly formed folds, as illustrated diagrammatically in Fig. 1.

70 The roll 56 is so located that the folded web 54 will be deposited on the inclined portion of the belt 33. The web will therefore enter the drying apparatus in a succession of overlapping folds and at the travel end of each belt within the drying 75 apparatus per se, the successive web folds are

tumbled indiscriminately onto the web supporting portion of the next lower belt. This action not only completely reverses the position of the web, but also reverses the direction in which the several folds lie. 5

By this method of handling the web, it is possible to considerably hasten and render the drying operation more effective because it is contemplated that the heated air will issue from the ducts at such a velocity and in such a volume that 10 the successive folds will be subjected to a substantially floating or billowing action due to the folds being lifted or separated by the impact of the air streams directed against the opposite side edges and between the folds of the web. 15 The dampers may be adjusted to secure a substantially uniform delivery of the air throughout the length of the ducts and also to secure any desired degree of drying by varying the quantity of air impinging on the web. Moreover, the 20 periodic turning over of the moving web and the reversing of the positions of the folds insures a complete drying of both sides of the web, while by crimping and moving the web in a sinuous path through the apparatus, the capacity-space 25 efficiency of the latter is obviously increased over that of the festoon type of drying rack. After contacting the folds of the web, the air passes freely away from the apparatus and may be exhausted to the atmosphere by suitable fan equipment. 30

In Fig. 3 is illustrated a modified type of duct 58 which is generally similar to those already described, except that a longitudinal slit 59 is substituted for the spaced apertures 49. Dampers 35 may also be and are preferably employed with this type of duct.

I claim:

1. A method of drying a continuous web of material comprising forming the same in a succession of overlapping folds, and carrying the folded web past streams of a drying medium directed against the opposite side edges of the web, the impact of the streams on each other and on the web causing the latter to have a billowing action 45 sufficient to separate the folds for intimate contact with the medium.

2. A method of drying a continuous web of material comprising forming the same in a succession of overlapping folds, and carrying the folded web along a succession of substantially horizontal courses in a substantially sinuous path from an upper to a lower elevation while exposing the web to streams of a drying medium directed against the opposite side edges of the web, 55 the impact of the streams on each other and on the web causing the latter to have a billowing action sufficient to separate the folds for intimate contact with the medium, alternate courses of the web moving in the same direction and the 60 transfer of the web between successive courses being effected by a gravity drop of the web folds.

3. A drying apparatus for drying a web of material comprising a plurality of moving, endless belts spaced from each other in a vertical direction, the web supporting portions of alternate belts running in the same direction whereby the web is moved in a sinuous path through the apparatus, means for continuously delivering a web to the uppermost belt in a succession of overlapping folds, and means extending along the opposite sides of the supporting portions and positioned to direct streams of a drying medium against the opposite side edges of the folded web. 65

4. A drying apparatus for drying a web of ma- 70

5 terial comprising a continuously moving, endless belt, means for continuously delivering a web to the belt in a succession of overlapping folds, and means extending along the opposite sides of the web supporting portion of the belt and positioned to direct streams of a drying medium against the opposite side edges of the folded web in sufficient volume and at a sufficient velocity to cause the web to have a billowing action sufficient to separate the folds for intimate contact with the medium.

10 6. A method of drying a continuous web of material comprising forming the same in a succession of reclining folds, and carrying the folded web past streams of a drying medium directed against the opposite side edges of the web, the impact of the streams on each other and on the web causing the latter to have a billowing action sufficient to separate the sides of the folds from each other, respectively, and from the remainder of the web for intimate contact with the medium.

15 7. A method of drying a continuous web of material comprising forming the same in a succes-

10 sion of folds, and carrying the folded web past streams of a drying medium directed against the opposite side edges of the web, the impact of the streams on each other while passing through the folds above and below the web imparting a shaking movement to the web and facilitating the drying action of the medium.

15 8. A drying apparatus for drying a web of material comprising a continuously moving, endless belt, means for continuously delivering a web to the belt with spaced portions of the web resting on the belt and other portions spaced from the belt and forming therewith ducts extending transversely of the web and means extending along the opposite sides of the web supporting portion of the belt and positioned to direct streams of a drying medium against the opposite side edges of the web, the impact of the streams on each other while passing through the ducts above and below the web imparting a shaking movement to the web and facilitating the drying action of the medium.
